(57) **CLAIM**

The ornamental design for a stanchion ring, as shown and described.

DESCRIPTION

FIG. 1 is a perspective view of a stanchion ring;

FIG. 2 is a rear perspective view of a stanchion ring;

FIG. 3 is a front view of a stanchion ring;

FIG. 4 is a rear view of a stanchion ring;

FIG. 5 is a top view of a stanchion ring;

FIG. 6 is a bottom view of a stanchion ring; and,

FIG. 7 is a side view of a stanchion ring.

The portions of the figures shown in broken lines depict environmental subject matter and form no part of the claim.
